United States Patent Office

CYRUS H. MERRICK, OF PITTSBURG, PENNSYLVANIA.

Letters Patent No. 68,377, dated September 3, 1867.

IMPROVEMENT IN STEAM ENGINES.

The Schedule referred to in these Letters Patent and making part of the same.

TO ALL WHOM IT MAY CONCERN:

Be it known that I, CYRUS HENRY MERRICK, of Pittsburg, in the county of Allegheny, and State of Pennsylvania, have invented a new and useful Improvement in Steam Engines; and I do hereby declare the following to be a full, clear, and exact description thereof, reference being had to the accompanying drawings, making a part of this specification, in which—

Figure 1 is a top view of the valve-chests and cylinder, the cover of the chests, the valves, and valve-rods being removed so as to show the valve-seats and ports.

Figure 2 is a vertical cross-section of the cylinder, valve-chests, valves, etc.

Figures 3 and 5 show a vertical section formed by planes passing longitudinally through the cylinder and balancing-valve in the line $y z$, fig 2; and showing the positions of the balancing-valve at different points of the stroke; and

Figures 4 and 6 are also sectional views formed by planes passing longitudinally through the cylinder and steam-valve in the line $x z$, (fig. 2,) and also showing the steam-valve in the two positions it occupies at different points of the stroke.

Like letters of reference indicate like parts.

The design of my invention is to utilize more perfectly than has heretofore been done the force of steam, hot or compressed air, or other fluid motors, as applied to the production of rotary motion, by means of a cylinder, piston, crank, and other appliances well known and in common use for such purposes.

The office of the crank in the steam engine, it is well known, is to transmit the power of the steam, and convert the reciprocating motion of the piston into rotary or circular motion. It is also manifest that at two points in the stroke, commonly called the "dead-points," the crank can transmit no power, from the fact that at these points it is acting in the line of stroke, and has no lever value. After passing the dead-points its value commences, and increases but very slowly to at or near the end of the first quarter or third of the stroke, from which point it increases with great rapidity, so that the maximum value of the crank as a lever and as a transmitter of power is attained when at right angles to the line of stroke, or, in other words, at or near half stroke. For the same reasons the leverage of the crank, and consequently its value, decrease with equal rapidity from such maximum point, till at the other dead-point it entirely disappears. Hence it is evident that a material saving will be effected, if, instead of applying the motive power to the piston at the beginning of the stroke, where it has no value, and continuing such application to the end of the stroke, where its value disappears, we concentrate the power on or apply it to the piston during that portion of the stroke where the position of the crank gives it its greatest value. In the ordinary construction of engine such concentration is partially attained by cutting off the steam before reaching the end of the stroke, though this is done for another reason, but it is only partially attained, since it still remains necessary to admit the motor to the cylinder at the commencement of each movement or stroke of the piston in order to avoid the vacuum and consequent back pressure which would be caused by deferring its admission.

In my invention I propose to obviate this difficulty, and utilize the steam to the greatest possible extent by not admitting live steam into the cylinder of the engine during the first quarter or third of the stroke, using the steam so admitted till the last third or quarter of the stroke is reached, at which points the steam and exhaust-ports are both closed. The points of opening and closing the steam and exhaust-ports may be varied, so as to be at such distances from the ends of the stroke as may be found most advantageous. I thus use the live steam only when the position of the crank enables me to use it most effectively. And to obviate the difficulty of back or retarding pressure at the commencement and end of the stroke, I open a separate communication between the two ends of the cylinder for the purpose of permitting the exhaust steam in the cylinder to pass back of the piston-head, and thereby I secure for the piston-head a perfect balance. The steam will pass freely through such communication from the front to the rear of the piston-head, and thus prevent the formation of a vacuum, obviate back pressure, and equalize the pressure exerted on opposite sides of the piston-head.

The nature of my invention, then, consists in balancing the piston-head of an engine while the crank is passing the dead-points, and for any desirable part of the stroke before and after, by the use of exhaust

while the crank is approaching to, passing, and receding from the dead-points or centres during any desirable portion of the stroke, substantially as and for the purposes above described.

3. So constructing and arranging the steam-valve and ports of a steam engine as to admit steam to the cylinder during the middle of each stroke, and for a greater or less proportion of such stroke, in combination with one or more openings or communicating passages from end to end of the cylinder, fitted with a valve or valves, or other suitable device for permitting or preventing the flow of steam in order to balance the piston, substantially in the manner and for the purposes hereinbefore set forth.

I testimony whereof I, the said CYRUS HENRY MERRICK, have hereunto set my hand in the presence of—

CYRUS HENRY MERRICK.
